BLANK FEEDING AND FLEXING MECHANISM

Allan M. Cameron, Chicago, Ill., assignor to
Cameron Can Machinery Co., Chicago, Ill., a
corporation of Illinois

Application April 6, 1940, Serial No. 328,181

2 Claims. (Cl. 153—54)

This invention relates in general to mechanisms for feeding and flexing metal blanks, such, for instance, as tin plate blanks which are customarily employed in making the bodies of tin cans.

In order that the bodies may be truly circular in form when produced from blanks by a body making machine, the blanks, in accordance with modern practice, are flexed in opposite directions so as to break the grain of the metal and render the blanks pliant so that they will bend into truly circular form, thereby obviating "flats" in the formed bodies.

One of the purposes of my present invention is to provide a grain breaking or blank flexing mechanism which will be simple in construction and consist of a minimum number of parts so that it will be economical to produce and operate, and at the same time will be reliable in operation.

Another feature of my invention resides in the simplicity of its construction, which enables it to be mounted on the frame of the machine and located between the magazine and body maker so that the blanks may be fed in a right line from the magazine through the flexing mechanism into the body maker without change of direction.

Other advantageous features are inherent in the ready adjustability of the flexing mechanism and in the safety stop which automatically stops the machine in the event of the simultaneous delivery to the flexing mechanism of more than one blank.

A preferred embodiment of my invention is illustrated on the accompanying drawings from which its structure, operation and advantages should be readily apparent.

Referring to the drawings:

Fig. 1 is a longitudinal sectional view through a mechanism embodying my invention;

Fig. 2 is a fragmentary similar view on an enlarged scale illustrating the passage of a blank through the flexing mechanism; and

Fig. 3 is a vertical sectional view on the line 3—3 of Fig. 1.

Referring now to the drawings more in detail, reference character 5 indicates generally the frame work of the front or receiving end of a body maker. The frame carries a table upon which the blanks are delivered at one side by the flexing mechanism, the table comprising the removable wear plate 6 next to the flexing mechanism and the other supporting portions 7 and 8 over which is disposed a hold down plate 9

5 by which the blanks 11 are held flat upon the table as they are fed to the various mechanisms of the body maker for operating upon them.

Any suitable feed mechanism may be used in 10 the body maker, and in Fig. 1 there is illustrated a conventional type comprising a pair of slide bars 12 equipped with feed dogs 13 by which the blanks are intermittently advanced through the machine.

At one side of the table there is mounted upon 15 the machine frame a magazine adapted to contain a supply of blanks and comprising a base 14 and uprights 15 between which the blanks are disposed. The lowermost blanks are supported in the magazine in the manner illustrated by shoulders 16 and 17 in the customary manner, and the bottom blank is flexed and pulled downwardly between the shoulders and deposited upon the base 14 by one or more reciprocating suction devices 18 in a manner common in this art. A transversely reciprocating feed dog 19 advances the blank resting upon the base plate 14 toward the left viewing Fig. 1 into the bight of the rolls of the flexing mechanism.

The flexing mechanism per se comprises a 20 pair of uprights 21 and 22 supported upon the machine frame or from the magazine and having disposed between them a pair of flexing rolls 23 and 24, respectively. The lower roll 23, which 25 is of uniform diameter from end to end, is journaled in roller bearings 25 and 26 in the uprights and is held against endwise displacement by bolts and washers 27 and 28 at each end.

The upper roll 24 is hollow and rotatably supported 30 by roller bearings 29 and 31 upon a stationary shaft or rod 32 extending between the uprights. The shaft 32 is carried in vertical reciprocable blocks 33 and 34 yieldingly urged 35 downwardly to press the roll 24 toward roll 23 by springs 35 and 36, the tension of which may be regulated by adjusting screws 37 and 38.

It will be observed from Fig. 3 that roll 24 40 is relieved, or, in other words, is made of reduced diameter intermediate its ends leaving end portions 39 and 41 of slightly larger diameter to engage the roll 23. The reduced or working portion of the roll 24 is, consequently, spaced from the roll 23 a distance somewhat less than 45 the thickness of the blanks to be operated upon, thereby facilitating the entrance of the leading ends of the blanks into the bight of the rolls. This insures that the blanks will be immediately caught between the rolls and fed forwardly 50 without delay and obviates the necessity of in-

dependent spacing means or adjusting devices for spacing the rolls apart.

Rearwardly of the roll 24 there is positioned for vertical adjustment a guard or guide 42 having a curved lower end portion 43 disposed slightly above the bight of the rolls 23 and 24 so as to permit direct entrance of the forward end of blank 11 beneath this guide into the bight of the rolls. Forwardly of the roll 24 there is mounted for vertical adjustment upon a bolt or bolts 44 a guard or guide 45 curved to present its lower end 46 rearwardly of and slightly below the bight of the rolls.

The bearing blocks 33 and 34 are rigidly connected by an integral cross member 47 which carries intermediate its ends a vertically adjustable rod 48 aligned with a finger 49 projecting from a switch 51 of any preferred type. This switch is adapted to be actuated by the rod 48 to shut off the driving motor for the mechanism in the event that two blanks instead of one should accidentally be fed between the rolls. The average blank being operated upon is approximately $10/1000$ of an inch thick. The clearance between the working portions of rolls 23 and 24 is approximately $7/1000$ of an inch so that each time a single blank passes between the rolls, the bearing block of roll 24, and, consequently, the rod 48 are elevated about $3/1000$ of an inch. The rod 48 is so adjusted that this normal movement of the rod will not actuate the switch 51. In the event, however, that two blanks should be simultaneously fed between the rolls, the upper roll 24 will rise approximately $13/1000$ of an inch, which is sufficient to cause the actuation of switch 51 by the rod 48, thereby stopping the machine to permit rectification of the error before any damage to the body maker has been caused.

Roll 24 is provided at one end with gear teeth 52 meshing with companion teeth 53 on roll 23 so that these rolls rotate in opposite directions. Roll 23 is driven through a pinion 54 meshing with the teeth 53 and with a gear 55 which may be driven through a belt or chain 56, which in turn is driven by a motor, the supply circuit of which is controlled by the switch 51.

The mechanism embodying my invention operates in the following manner:

The lowermost blank 11 in the magazine is deposited upon the magazine base 14 by pneumatic suction cups 18 and is then moved to the left viewing Fig. 1 by the feed dog 19 beneath the lower end 43 of guard 42 into the bight of the rolls 23 and 24.

It will be observed that roll 24 is laterally offset with respect to roll 23, that is, the axis of roll 24 is positioned rearwardly of a vertical plane coincident with the axis of the roll 23. The result is that when the forward edge of a blank is delivered from between the rolls, it is directed downwardly against the upper surface of plate 6 by which it is deflected horizontally, thus bringing the blank into engagement with the end 46 of guide 45. The offset position of the rolls causes the portion of the blank resting upon the base plate 14 to be elevated against the lower edge of guide 42, as illustrated in Fig. 2. From this figure, it will be apparent that as the blank is fed through the flexing mechanism, the rolls, because of their offset relation, flex the blank downwardly, and thereafter as the blank travels along the plate 6, it is flexed in the opposite direction by the cooperative action of the plate and the end 46 of guide 45. In this

manner the rolls, by reason of their offset relation and in conjunction with the guides 42 and 45 and the plate 6, produce a flexation of each blank, first in one direction and then in the opposite direction, sufficiently to break the grain of the metal and render the blank pliant so that it will form a truly circular can body devoid of objectionable "flats." The degree of flexation may be varied as desired by vertical adjustment of the guide members 42 and 45. In the event that more than one blank is fed into the bight of the rolls, the mechanism will be stopped by actuation of the switch 51 in the manner previously explained.

The structural details illustrated and described may obviously be varied within considerable limits without departure from the essence of my invention as defined in the following claims.

I claim:

1. A mechanism for flexing sheet material, which comprises a pair of rolls having parallel axes and providing a bight between said rolls through which said sheet material is advanced from a feed side to a discharge side of said rolls, a guide member for said sheet material positioned closely adjacent one of said rolls on the feed side of said rolls and having a converging portion extending into the space between said rolls and terminating in a reduced end directed toward and closely adjacent said bight, said end having a guiding surface directed toward said other roll and contacting said sheet material to force the same toward said other roll out of a plane passing through said bight and tangent to said rolls so as to flex said sheet material in one direction about said other roll, a second guide member for said sheet material positioned closely adjacent said one roll on the discharge side of said rolls and having a converging portion extending into the space between said rolls and terminating in a reduced end directed toward and closely adjacent said bight, said end of said second guide member having a guiding surface directed towards said other roll, and a plate extending from a position adjacent said other roll on the discharge side thereof away from said other roll past said end of said second guide member and across the path of the sheet material discharged from said rolls at an angle to said path for flexing said sheet material in the opposite direction about said guiding surface on said second guide member.

2. A mechanism for flexing sheet material, which comprises, an upper roll and a lower roll, having horizontal roll axes and providing a bight between said rolls through which said sheet material is advanced from a feed side to a discharge side of said rolls, said upper roll being offset relative to said lower roll toward the discharge side of said rolls, a horizontal table on the feed side of said rolls substantially level with said bight from which said sheet material is fed, a guide member for said sheet material extending downwardly closely adjacent said upper roll on the feed side of said rolls and having a curved converging portion extending into the space between said rolls and terminating in a reduced end directed toward and closely adjacent said bight, said end having a guiding surface directed downwardly toward said lower roll and contacting said sheet material to force the same toward said table and lower roll out of a plane passing through said bight and tangent to said rolls so as to flex said sheet material in one direction about said lower roll, a second guide member for said sheet material positioned closely adjacent said upper roll

on the discharge side of said rolls and having a curved converging portion extending into the space between said rolls and terminating in a reduced end directed toward and closely adjacent said bight, said end of said second guide member having a guiding surface directed toward said lower roll, and a horizontal table positioning lower than said first mentioned table extending from

5 a position adjacent said lower roll on the discharge side thereof away from said lower roll past said end of said second guide member and across the path of the sheet material discharged from said rolls at an angle to said path for flexing said sheet material in the opposite direction about said guiding surface on said second guide member.

ALLAN M. CAMERON.
